LIFEBOAT DAVIT

Frank C. Simonds, Moylan, Pa.

Application January 22, 1943, Serial No. 473,229

2 Claims.

(Cl. 9—37)

This invention relates to new and useful improvements in life boat davits.

Present emergency marine regulations, particularly in the merchant service, require that the ships' life boats be carried in an outboard position ready for lowering, instead of in the inboard position resting in the usual chocks which are secured upon the deck surface. This regulation, of course, is intended to enable the life boats to get away in as short a time as possible in the event a ship may be torpedoed or strike a mine.

The conventional type of davit now in use on ocean-going ships is designed for the inboard carriage of life boats and not for carrying boats in the outboard, or swung-out position in which they are suspended over the side of the ship ready for lowering. This is so for the reason that such davits are not constructed to withstand the load and shocks resulting from fore and aft pitching of the ship in a sea with the life boat in swung-out position and supported wholly from the davit, and it has occurred on several occasions that davit arms or booms have broken away from their supporting structures or frames under such loads or as the result of sudden shock or impact. Too, the davit arms have been known to break away from their housings or support frames as a result of the shock caused by the explosion of a torpedo or mine.

With the foregoing in mind, an object of the present invention is to provide a life boat davit embodying certain novel features of construction and arrangement which provide adequate support for a life boat against fore and aft stress and strain due to load and shock when the boat is carried in the outboard, or swung-out, position of the davit.

Another object of the invention is to provide a davit of the character set forth wherein the davit arm is firmly and adequately supported with respect to its housing and base structure to prevent breaking away of the davit arm from the base or support as a result of excessive fore and aft loading and shocks.

A further object of the invention is to provide a lifeboat davit of the stated type wherein the novel features of construction and arrangement contemplated by the present invention may be embodied and adapted to both new and existing davits without material alteration of the fundamental davit structure and operation.

These and other objects of the invention and the various features of the construction and operation thereof are hereinafter more fully set forth and described, and shown in the accompanying drawing in which:

Fig. 1 is an end elevation of a davit constructed in accordance with my invention.

Fig. 2 is a side elevation thereof.

Fig. 3 is a view in perspective of a structural element of the invention, and

Fig. 4 is an enlarged fragmentary view in section taken on line 4—4, Fig. 2.

Referring now more particularly to the drawing, the form of davit shown in Figure 1 is of generally conventional construction and comprises a davit arm or boom 1 having at its base or lower end a toothed quadrant 2. The davit arm 1 is mounted upon a generally rectangular support or frame structure 3 having along its lower base portion a toothed rack 4 on which the quadrant 2 of said arm or boom 1 is arranged to roll. The arm or boom 1 carries a pivot pin 5 fixed to the side of a block 6 which is free to move along a guide bar 7. The lower part of the block 6 has a threaded bore therethrough forming a nut through which passes a screw element 8, and the latter is actuated by a crank 9 to roll the quadrant 2 over the rack 4 of the frame or support structure 3 thereby moving or 10 swinging the arm or boom 1 in an athwart-ship direction between outboard and inboard positions in the conventional manner.

From this construction it will be observed that the davit support or frame structure 3 extends 30 in an athwartship direction and while it provides support for the davit arm or boom 1, and for the weight of the life boat athwartship substantially no support or stability in a fore and aft direction is afforded the davit and boat carried thereby, and this is particularly true when the boat is carried in the outboard position, or swung-out ready for lowering as present regulations require. Furthermore, connection of the davit arm or boom 1 to its supporting frame or structure 3 is provided solely by the pin 5, and this pin will not withstand the shocks and load to which the davit boom or arm is subjected in a fore and aft direction with a life boat to its outboard position suspended over the side of the 40 ship.

According to the present invention, therefore, the davit supporting frame or structure 3 is constructed in substantially L-shape and provided with a leg or portion 10 which extends in a direction fore and aft the ship substantially at right angles to the supporting frame portion 3 which extends in an athwartship direction as 50 previously described. This construction provides not only adequate support and stability to the davit in the athwart-ship direction but also provides support thereto against load and shocks 55 acting on the davit in a fore and aft direction.

In addition, and to provide support and stability to the davit boom or arm 1 relative to the support or frame structure in a fore and aft direction, there is provided, on the athwart-ship extending frame or support portion 3, a guide member 11 which is constructed and arranged, as hereinafter set forth, to provide an interlock with the davit arm or boom 1.

More particularly, the guide member 11 has an arcuate upper edge 12 which curves slightly downwardly in an outboard direction corresponding to the arc described by the davit boom or arm as it moves from the extreme inboard to the extreme outboard position upon actuation by the screw 8.

The guide member is provided with an arcuate slot 18 corresponding to the curvature of the member upper edge 12. Secured to the outer face of the davit arm 1 and extending through the slot 18 of the member 11 is a pin or stud 19 having at its extremity an enlarged head portion 20 operable normally to prevent withdrawal of said stud 19 from the said slot 18.

By this construction it will be observed that in all positions of the davit arm 1 as it moves between the inboard and outboard positions, the pin or stud 19 provides an effective interlock between the davit arm 1 and the member 11 of its supporting frame or structure. This arrangement provides substantial stability and support to said arm with respect to its frame structure in a direction fore and aft the ship and, in conjunction with the frame or support portion 10, provides strength and support to the davit as a whole sufficient to withstand fore and aft stresses and strains resulting from pitching of the ship and from shocks received by the ship when the life boats are suspended in their outboard or swung-out position over the side of the ship. In addition the provision of the pin and slot connection provides a positive stop construction which serves effectively to hold the davit arm 1 securely in its frame or support 3 and prevents said arm from jumping out of its support structure as the result of sudden shocks or impact sufficient to cause shearing of the drive pin 5 and collapse of the davit.

To permit removal of the davit arm or boom 1 for purposes of repair or replacement, the slot 18 of the frame member 11 is enlarged as indicated at 17 (see Fig 3) for passage of the headed pin or stud 19 from engagement with slot 18 when it is desired to disengage the davit arm 1 from its housing or frame 3 after disconnection of the drive pin 5 from the drive block 6.

It will be obvious, of course, that the frame portion 10 and the guide member 11 may be fabricated separately and bolted, welded or otherwise secured in their proper place upon the frame 3. On the other hand, these members 10 and 11 may either or both be cast integral with the main frame or support structure 3. These possibilities react to advantage since it permits of the relative rapid and easy adaptability of the invention to existing davits as well as to davits now being, or to be, manufactured.

In the case of ships having a plurality of boat davits extending in a line along opposite sides of the ship, the davit frame brace portions or legs 10 may be made generally rectangular in shape and interposed between and secured to the adjacent athwart-ship davit frame members 3. In this manner a single intermediate brace portion 10, extending along and secured to the

ship's deck in the fore and aft direction, may serve to brace the two adjacent frame structures 3 of adjacent davits, thereby providing adequate support therefor in a minimum of space which is quite important, particularly in the case of large passenger ships, where rows of life boats must be accommodated along opposite sides of the ship.

From the foregoing, it will be observed that the present invention provides a life boat davit which is characterized by its stability against load and shocks producing stresses and strains acting in the fore and aft direction of the ship. Too, the invention provides a davit wherein the arm or boom is firmly and adequately restrained and supported against movement in a fore and aft direction with respect to its base or housing structure, and against displacement therefrom. Furthermore, the invention is one that is susceptible of adaptation to, and embodiment in, both existing davits and those being, or to be, manufactured.

While a certain embodiment of the invention has been illustrated and described herein, the invention is not limited to such disclosure but that changes and modifications may be made and embodied therein within the scope of the claims.

1. In a ship's boat davit comprising a boom arranged to swing in a vertical plane in an athwart-ship direction between inboard and outboard positions, a frame structure pivotally supporting said boom secured to the deck of the ship and comprising a first frame portion extending athwart-ship and parallel to the plane of movement of the boom and a second frame portion extending in the fore and aft direction of the ship outwardly from the first frame portion, means on the first frame portion having a slot 30 therein, and a pin carried by the boom and movable within said slot, said pin having an enlarged head portion normally preventing removal of the pin from said slot to provide an interlock between said boom and first frame portion preventing relative lateral movement between said boom and frame in the fore and aft ship direction, the second frame portion and said interlock cooperating to stabilize and strengthen the davit against load stresses and strains acting in the fore and aft direction of the ship.

2. In a ship's boat davit comprising a rigid frame secured in an athwart-ship direction to the deck thereof, a boom pivotally supported by said frame arranged to swing in a vertical plane parallel to the frame from an inboard position to an outboard position, and means for actuating said boom, a brace member secured to the frame and deck and extending outwardly from said frame along said deck in the fore and aft direction of the ship, means on the first frame portion having a slot therein, and a pin carried by the boom and movable within said slot, said pin having an enlarged head portion normally preventing removal of the pin from said slot to provide an interlock between said boom and frame preventing relative lateral movement between the boom and frame in the fore and aft direction of the ship, said brace member and the interlock between the boom and frame cooperating to stabilize and strengthen the davit against load stresses and strains in a direction fore and aft the ship.

FRANK C. SIMONDS.
